UNITED STATES PATENT OFFICE.

JOHN WYBERD, OF NEW YORK, N. Y.

NIGHT-LIGHT REFLECTOR.

Specification forming part of Letters Patent No. 27,855, dated April 10, 1860; application for Re-issue filed November 13, 1873.

REISSUED

To all whom it may concern:

Be it known that I, JOHN WYBERD, of New York, in the county of New York and State of New York, have invented a new and useful Improvement in Night-Light Reflectors called "The Argento-Crystal Dioptric Illuminator;" and I do hereby declare that the following is a full, clear, and exact description of the same, reference being had 10 to the annexed drawing, forming part of this specification, in the several figures of which similar characters of reference denote the same part.

Figure 1 is a top view of the reflector. 15 Fig. 2 is a vertical section on axis of the gas pipe.

The nature of my invention consists in suspending over the burner a reflector of octagonal shape composed of series of inclined metallic plates each series decreasing in circumference and placed above each other, and connected by standards of wire or iron, leaving the space between them open for ventilation. The surfaces of the plates 20 are also corrugated so as to assist in diffusing the light.

In the drawing B, B, are the burners, S an ordinary glass shade for mellowing the light, R the reflector composed of the inclined, corrugated, plates *p* arranged in octagonal 30 shape and connected by standards *a*, *a*, leaving the space between them open for ventilation each series or row of plates being smaller in circumference and graduating toward the top, by this means the light is reflected and diffused through the room.

I disclaim the arrangement of surfaces as described considered as mere ventilators, but claim as new

The dome like arrangement of a system 40 of corrugated reflectors with alternate ventilating spaces as set forth.

In testimony whereof I have hereunto signed my name before two subscribing witnesses.

JNO. WYBERD.
